United States Patent Office.

REUBEN M. REYNOLDS, OF OAKVILLE, MICHIGAN.

Letters Patent No. 97,444, dated November 30, 1869.

IMPROVED LIFTING-JACK.

The Schedule referred to in these Letters Patent and making part of the same.

To all whom it may concern:

Be it known that I, REUBEN M. REYNOLDS, of Oakville, in the county of Monroe, and State of Michigan, have invented a new and valuable Improvement in Lifting-Jack; and do hereby declare that the following is a full, clear, and exact description of the construction and operation of the same, reference being had to the annexed drawings, making a part of this specification, and to the letters and figures of reference marked thereon.

Figure 1, of the drawings, is a front view.

Figure 2 is a detail.

My invention relates to lifting-jacks; and

It consists in a novel arrangement of devices intended to serve efficiently as a means for lifting and sustaining carriages, while the process of lubricating the wheels is carried on, and for other similar uses.

A and B, of the drawings, represent two standards or posts, arranged with reference to each other, upon an angle, as shown in fig. 1. These posts are respectively held in place by the plates *a* and *c*, on the front sides, and by a long plate on their rear, extending from their tops to a point about opposite the lower side of plate *c*.

D represents the lifting-post, arranged between the standards A and B, and the plates thereon, as shown.

It sits loosely between said standards and plates, and has upon its front side a series of openings, marked *d*, on the drawings. These openings are respectively adapted to receive the bent point of the lifting-rod hereinafter mentioned.

Letter H represents a staple, having its points respectively inserted in the standards, and one of which points passes through and serves as a fulcrum for the lever hereinafter described.

K is the lifting-lever, pivoted upon one of the points of the staple H, and also firmly attached to the block S, as hereinafter described.

S is a metallic block, cast with a groove adapted to receive the head of lever K, and also with an ear, *v*, to receive and aid in operating the rod *y*. The circle of said block, represented by *a'*, fits closely to the front side of standard A, and the same point of the staple that passes through the lever K, passes also through the centre of the circle, and serves as a pivot for its movements.

R is a strong rod, bent at each end, so as to form right angles with the body, one of which bent ends enters the ear *v*, while the other is operated at will in the openings *d* of the lifting-post.

To operate my device, one end of the rod R is placed in an opening, *d*, and the lever is pressed down. When the lever is forced downward to such a point that the rod R becomes perpendicular with the lifting-post, or a little beyond that point, the weight lifted is sustained automatically by the jack itself, and requires neither hand or weight upon the lever.

What I claim as my invention, and desire to secure by Letters Patent, is—

The lifting-jack herein described, having posts A, B, and D, staple H, lever K, block S, and bent rod R, constructed and arranged to operate substantially as specified.

In testimony that I claim the above, I have hereunto subscribed my name, in the presence of two witnesses.

REUBEN M. REYNOLDS.
